UNITED STATES PATENT OFFICE.

SPENCER A. BARKER, OF DEPORT, TEXAS, ASSIGNOR OF ONE-HALF TO WILLIAM R. MAGILL, OF DEPORT, TEXAS.

PLOW.

1,156,831.

Specification of Letters Patent.

Patented Oct. 12, 1915.

Application filed August 19, 1914. Serial No. 857,547.

To all whom it may concern:

Be it known that I, SPENCER A. BARKER, a citizen of the United States, residing at Deport, in the county of Lamar and State of Texas, have invented certain new and useful 5 Improvements in Plows, of which the following is a specification, reference being had to the accompanying drawings.

The present invention relates broadly to 10 new and useful improvements in plows and as its principal object aims to provide in connection with a plow, an adjustable knife blade which is adapted to work in the rear of the plow share for cutting roots and the 15 like and for steadyng the plow so that it may be easily guided.

A more specific object of the invention is 20 to provide in connection with a plow, a cutter blade and to accompanying the cutter blade with adjusting means of such construction that a maximum range of adjustment is provided.

The above and other incidental objects of 25 a similar nature, which will be hereinafter more specifically treated are accomplished by such means as are illustrated in the accompanying drawings, described in the following specification, and then more particularly pointed out in the claims which 30 are appended hereto, and form part of this application.

With reference to the drawings, wherein 35 there has been illustrated the preferred embodiment of this invention, as it is reduced to practice, and throughout the several views of which similar reference numerals designate corresponding parts, Figure 1 is a side elevation showing the improved device; and Fig. 2 is a sectional view on the 40 line 2—2, of Fig. 1.

As disclosed in the accompanying drawings, the improved device includes a plow beam 1, the rear end of which is curved downwardly to provide a standard 2. 45 Bolted to each face of the standard at its lower end, are foot plates 3. A bolt 4 extends through the standard above the foot plates and to this bolt are pivotally connected the lower ends of a pair of handles 5. 50 Pivotsly secured to the opposite faces of the beam are a pair of rearwardly extending brace rods 6, the rear ends of which are provided with a plurality of openings 7 adapted to receive bolts 8, which extend through 55 openings in the handles and serve to adjustably connect the brace rods 6 and handles.

Pivotsly secured at their forward ends, between the foot plates 3, are a pair of knife bars 13 which extend rearwardly from the foot plates and carry between their adjacent faces, a knife blade 14. While I have shown two guide bars 13, it is of course obvious that only one of these members need be employed, under some conditions. Pivotsly connected to the rear ends of the 65 guide bars, are the lower ends of a pair of brace bars 15. The upper ends of these brace bars are provided with a plurality of openings 16, through which a rod or equivalent fastening device 17 is passed and engaged in the handles 5, whereby the knife bar may be raised or lowered to engage the 70 knife different depths in the ground.

I now desire to explain that the guide 75 blade and associated parts of the invention are adapted to be used in connection with a turning plow, middle breaker or any other type of ground engaging implement. While no ground engaging element, other than the 80 knife blade has been disclosed in the accompanying drawings, it will be obvious that an element of this character may be readily attached to the main standard by a suitable auxiliary standard or clamp, to work in advance of foot pieces.

Attention is now directed to the fact that 85 the depth to which the knife blade 14 may be engaged in the ground can be controlled not alone by the adjustment of the brace bars 15 with respect to the handle 5, but also 90 by the adjustment of the angle of inclination of the handles 5. Thus an unusually wide range of adjustment is possible with the present construction.

Having thus fully described my invention, what I desire to claim and secure by Letters Patent is:

1. A plow including a beam, a standard, a knife blade, means pivotally connecting the blade adjacent to the lower end of the standard, handles pivotally connected to the standard above the pivot of the blade, an adjustable connection between the rear end of the blade and the handles, and an adjustable connection between the beam and the 100 handles.

2. A plow including a beam, a standard, a pair of foot plates secured to the lower end of the standard on opposite sides thereof, a rearwardly extending knife bar pivotally 105 secured at its forward terminal between the foot plates, a knife blade secured to the bar,

handles pivotally connected to the standard above the pivot of the knife bar, an adjustable connection between the beam and the handles, brace members pivotally connected at its lower end to the knife bar, at the rear end thereof, said braces being pivotally connected at their upper ends to the handles and being adjustable with respect thereto,

whereby the angle between the knife bar and the handles may be varied.

In testimony whereof I hereunto affix my signature in the presence of two witnesses.

SPENCER A. BARKER.
